inventor:

James S. Andrews
J. M. Bell, M.D.

UNITED STATES PATENT OFFICE.

JAMES S. ANDREWS, OF NEW YORK, N. Y.

UNDERFRAME FOR CARS AND TENDERS.

No. 910,263.

Specification of Letters Patent.

Patented Jan. 19, 1909.

Application filed May 11, 1908. Serial No. 432,031.

To all whom it may concern:

Be it known that I, JAMES S. ANDREWS, a citizen of the United States, residing at New York city, in the county of New York and State of New York, have invented new and useful Improvements in Underframes for Cars and Tenders, of which the following is a specification.

My invention relates to cast steel underframes especially adapted for freight cars and engine tenders and its object is, primarily, to increase the strength of the underframe and at the same time reduce its weight and lessen the cost of manufacture.

Another object of the invention is to reduce the number of different sections of which the underframe is composed so that it can be made with only a few standard patterns.

In the accompanying drawings Figure 1 is a top plan view of an underframe embodying my invention. Fig. 2 is a longitudinal sectional view on the line 2—2 of Fig. 1. Fig. 3 is an elevation of the end sill. Fig. 4 is a sectional view on the line 4—4 of Fig. 1, showing the body bolster in elevation. Fig. 5 is a sectional view on the line 5—5 of Fig. 1, showing the cross tie, or needle beam, in elevation.

Referring to the drawings, the underframe comprises a single center sill 7 extending throughout the length of the underframe and made in a single casting, two end sills 8 made alike from the same pattern, two body bolsters 9 and two cross ties, or needle beams, 10, all made alike from the same pattern. Thus, these essential parts of the underframe can be made from three patterns, one for the center sill, one for the end sills and one for the body bolsters and cross ties.

The center sill 7 is made in a substantially inverted U-shape form in cross section and is provided at suitable intervals with openings 7' to reduce its weight, these openings being so disposed that they will not impair the strength of the sill. At the lower edges of the center sill are outwardly projecting lateral flanges 11 which preferably extend throughout its length to stiffen the sill and provide a rest and fastening part for the body bolsters and cross ties. A plurality of transverse guide lugs 12 are arranged in pairs at proper intervals on the top of the center sill for a purpose hereafter described. The middle part of the center sill is pref-

erably made deeper than the end parts for greater strength and the ends are reduced or offset at 13 to receive the end sills. Center bearings 14 are cast integral with the center sill and the latter may be provided above said bearings and at intervals throughout its length with interiorly located strengthening webs 15.

Each end sill is made in substantially L form and is provided at the center with a depending apron or buffer plate 16 having an opening 16' for the coupler. The end sills rest in the offsets 13 of the center sill and are bolted to cross webs 17 on the center sill.

The body bolster is cast in one piece with an arch 18 at the center conforming to the transverse section of the center sill and to fit snugly thereon. The top or connecting web 19 of the arch fits snugly between a pair of guide lugs 12 whereby the bolster is prevented from twisting or weaving and is held in rigid position square with the center sill. The bolster 9 (Fig. 4) rests upon the flanges 11 and is riveted or bolted thereto.

The cross ties, or needle beams 10 (Fig. 5) are made exactly like the bolsters 9 and are arranged in place on the center sill in the same manner. As the cross ties are located between the bolsters where the center sill is deeper than at the bolsters I provide flanges 20 on the center sill upon which the cross ties rest and to which they are riveted or bolted. The bolsters and cross ties are provided with side bearings 21 and are depressed at 9', 10', above the side bearings to receive the stringers 22 which may each extend in one piece throughout the length of the underframe. Lugs 23 are made integral with the bolsters and cross ties to support the sectional stringers 24 and the end sills have integral lugs 25 to support the stringers.

Each side sill consists of a Z-shape bar 26 which rests upon and is riveted or bolted to the ends of the end sills, body bolsters and cross ties and supports the wood sill 27. One end flange 26' of each side sill overlaps the ends of the bolsters, cross ties and end sills and the other end flange 26'' projects outwardly from said parts. The end posts 28 stand on the upper flange 8' of the end sill and a wood end sill 29 is arranged in the end sill 8. The end lining 30 of the car is fastened to the post 28 and the end siding 31 is fastened to the post 28 and to the wood end sill 29. If there should be any appreciable

longitudinal shrinkage of the center sill in casting the predetermined longitudinal interior dimensions of the car may be preserved by properly proportioning the width of the 5 wood end sills 29.

The transoms 32 may be made of angle iron and fastened in any suitable manner to the center and side sills. Braces 33 are arranged at each end of the underframe and 10 extend diagonally from the end sill, adjacent to the center sill, to the outer ends of the bolster, these braces being connected at their ends to the end sill and the bolster.

The principal parts of the underframe are 15 preferably made of steel castings and the construction is such that the cost of manufacture is greatly reduced by reason of the few parts and patterns required.

The weight of the underframe for a car 20 of a given capacity may be much less than has heretofore been possible while at the same time the strength of the underframe is increased.

What I claim and desire to secure by Letters Patent is:

1. In an underframe for cars and tenders, a center sill extending throughout the length of the underframe and made in one casting, said center sill being inverted U-shape in 30 cross section, and transverse strengthening webs located within said center sill.

2. In an underframe for cars and tenders, a center sill extending throughout the length of the underframe and made in one casting, 35 said center sill being inverted U-shape in cross section, center bearings integral with the center sill, and transverse strengthening webs located within the center sill above said bearings.

40 3. In an underframe for cars and tenders, a center sill extending throughout the length of the underframe and made in one casting, and guide lugs integral with the center sill and extending transversely across the top 45 thereof.

4. In an underframe for cars and tenders, an end sill made in one casting and L-shape in cross section, and an apron integral with 50 said end sill and depending therefrom between its ends.

5. In an underframe for cars and tenders, the combination of a center sill, transverse guide lugs on top of the center sill, and a transverse member made in one casting and 55 provided between its ends with an arch to receive said center sill, that part of the transverse member which passes over the center sill being arranged between a pair of said guides.

60 6. In an underframe for cars and tenders,

the combination of a center sill, a pair of bolsters each provided between its ends with an arch to receive the center sill, and a plurality of cross ties made like the bolsters and located between the ends of the center 65 sill.

7. In an underframe for cars and tenders, an end sill L-shape in cross section and arranged in a horizontal position, and a wood sill in the hooked end of said end sill. 70

8. An underframe for cars and tenders comprising a center sill extending throughout the length of the underframe and made in one casting, lateral flanges on said center sill, a pair of bolsters and a plurality of 45 cross ties made alike and each made in a single casting with an arch between its ends to receive the center sill, said bolsters and cross ties being arranged to rest upon said flanges, the ends of said center sill being offset, end sills secured in the offset ends of the center sill, and Z-bars fastened to the ends of the bolsters, cross ties and end sills, each of said side sills having one end flange overlapping the bolsters, cross ties and end sills 80 and its other end flange projecting outwardly 85 therefrom.

9. In an underframe for cars and tenders, a center sill having its end offset, and an end sill L-shape in cross section and seated in 90 said offset.

10. In an underframe for cars and tenders, a cast steel center sill made in substantially inverted U-shape in cross section and having transverse strengthening webs connecting its sides at intervals throughout its 95 length and below its top.

11. In an underframe for cars and tenders, a cast steel center sill made in substantially inverted U-shape in cross section and 100 having integral center bearings thereon.

12. In an underframe for cars and tenders, a cast steel center sill made in substantially inverted U-shape in cross section and having integral center bearings thereon, and 105 strengthening webs above said bearings and connecting the sides of the center sill.

13. In an underframe for cars and tenders, the combination of a transverse member having a central arch substantially inverted U-shape, and a center sill substantially inverted U-shape in cross section to fit in said arch and having strengthening webs connecting its sides and located at intervals throughout its length and beneath its top. 110
